CYLINDER TYPE RUBBER OARLOCK HOLDER

Sidney R. Messman, Sandpoint, Idaho

Application January 24, 1949, Serial No. 72,394

1 Claim. (Cl. 9—26)

1

This invention relates to an oar lock sleeve for an oar comprising a hollow cylinder of resilient material.

A primary object of this invention is to provide means to prevent the loss of an oar, without interfering with the normal use of the oar and the oar lock concerned.

Another object of this invention is to provide an oar lock sleeve which can be secured in place without nails or other metallic fasteners, the sleeve being simply slid down over one end of the oar to a position intermediate the ends thereof, after the oar lock has been first mounted on the sleeve.

Another object of this invention is to strengthen and reinforce the oar at the point where oars are likely to break, and it should also be noted that the sleeve will fit snugly on the oar so as to prevent moisture from reaching this portion of the oar, thus tending to prevent rot of this portion and consequent breakage.

Still another object of this invention is to provide an oar lock sleeve which is easily transferable from a broken oar to another oar, and which may be adjusted to suit the need of an individual user by sliding the sleeve along the shank of the oar.

Still another object of this invention is to provide the oar lock sleeve with a pair of external radially extending flanges on each end thereof to prevent the sleeve from slipping out of engagement with the oar lock, and also providing a more positive mounting for the oar on the boat.

Yet another object of this invention is to provide an oar lock sleeve which may be used with both metal and wooden oars and which is constructed of resilient material so that the operation of the oar will be rendered more quiet.

And a last object to be mentioned specifically is to provide an oar lock sleeve which is relatively inexpensive and practicable to manufacture, which is simple and safe as well as convenient to use, and which will give generally efficient and durable service.

With these objects definitely in view, this invention resides in certain novel features of construction, combination and arrangement of elements and portions as will be hereinafter described in detail in the specification, particularly pointed out in the appended claim, and illustrated in the accompanying drawings which form a material part of this application, and in which:

Figure 1 is a side elevational view of an oar with this car lock sleeve applied thereto.

Figure 2 is a three dimensional view of a por-

2

tion of an oar, an oar lock, and a sleeve according to this invention operatively connected therewith; and

Figure 3 is a vertical sectional view taken through the oar lock sleeve and showing a contiguous portion of an oar within the sleeve.

Similar characters of reference designate similar or identical elements and portions throughout the specification and throughout the different views in the drawing.

Referring now to the drawing in detail, this invention is adapted to be used with an environment including an oar which will have a shank portion 10 and a blade 12. The oar lock sleeve comprises a hollow cylinder of resilient, compressible rubber or other suitable material indicated at 14. An oar lock 16 having a depending integral pivot pin 18 is used with this invention and may be considered an element of this invention cooperating with the oar lock sleeve and the oar. The hollow cylindrical portion 14 is provided with a pair of external radially extending flanges 20, one on each end of the portion 14, these flanges 20 serving as reinforcing members and also serving to prevent the oar lock 16 from slipping out of engagement with the sleeve, during the use of the invention.

The operation of this invention will be clearly understood from a consideration of the foregoing description of the mechanical details thereof, taken in connection with the drawing and the above recitation of the objects thought to be achieved by this invention. In recapitulation, it may be added that one end portion of the sleeve 14 and the respective flange 20 thereon are collapsed to permit the ring 16 to be slipped on said sleeve, which is then forced under tension onto the shank portion 10 of the oar, the final positioning of the sleeve on the oar being determined by the particular need of the user of the device. The sleeve 14 is of a diameter to fit snugly within the ring 16. It will be clear that all the objects mentioned above will be accomplished by this invention and further description would appear unnecessary.

Obviously, minor variation in the construction and proportioning of the sleeve may be resorted to without departure from this invention and the scope of this invention should be determined only as limited by a proper interpretation of the terms used in the subjoined claim.

Having described the invention, what is claimed as new is:

A bushing for oar locks of the type including a pin and a ring thereon, comprising a collapsible

sleeve of resilient, compressible material for mounting under tension on the shaft of an oar, said sleeve being of substantial thickness and of a diameter to fit snugly within the ring thereon, and retaining flanges for the ring on the ends of said sleeve, said flanges being insertable through the ring when the end portions of the sleeve are collapsed.

SIDNEY R. MESSMAN.
